ELECTROSTATIC PRECIPITATOR SYSTEM

Morris Newman, Minneapolis, Minn.

Application October 30, 1943, Serial No. 508,336

14 Claims. (Cl. 183—7)

1

This invention relates to electrostatic precipitator systems and particularly to systems wherein ionization is produced under different potentials than that employed for precipitation of the ionized particles. It has been discovered that ionization may be produced by an alternating current having a frequency in the range from high audio frequencies to slightly below the low radio frequencies and having a unidirectional voltage component and that the degree of ionization may be conveniently and readily controlled automatically in such a system.

It is accordingly an object of the invention to provide an improved electrostatic precipitating apparatus and system wherein dust and micro-biological particles in the air and gas stream are charged by a high voltage alternating potential having a frequency in the range extending from high audio frequencies to a frequency slightly lower than the low radio frequencies, and a high voltage unidirectional component. It is also an object of the invention to provide an improved electrostatic precipitating system including a power source therefor, and more particularly to provide a system wherein the degree of ionization is automatically and conveniently regulated so as to prevent excessive ionization with resultant ozone and nitrous oxide formation.

It is also a purpose of the invention to provide safe electrostatic precipitator systems which are free from dangerous capacitors which have heretofore been used, and to provide safe electrostatic precipitator systems wherein the precipitator plates have a dual function. It is also an object to provide in such systems a safe high frequency energization obviating danger.

It is also an object of the invention to provide an electrostatic precipitating apparatus and system of portable nature, including a convenient, low-weight power pack for the apparatus.

Other and further objects are those inherent in the apparatus illustrated, described and claimed.

The invention is illustrated with reference to the drawings in which

Figure 1 is a sectional view through an electrostatic precipitating apparatus;

Figures 2, 3, 4 and 5 are wiring diagrams of varying forms of electrical circuit arrangements for supplying electrical power as a portion of the electrostatic precipitating apparatus and system of the invention;

Figures 6 and 7 are graphs illustrating the operation of the invention;

Figures 8 and 9 are schematic illustrations of

modified forms of the precipitating system, each showing a fragmentary part of the wiring diagram of the power supply; and

Figure 10 is an enlarged view, partly in section, illustrating an optional form of one adjunct of the apparatus.

Throughout the drawings corresponding numerals refer to the same parts.

Referring to Figure 1, there is illustrated a cross section through a precipitating apparatus wherein in the outer framework of container 10 is a rectangular cross section and may conveniently be composed of sheet metal. Upon the side walls 11 and 12 of the container are mounted oppositely spaced pairs of insulators 13 and 14 and 15 and 16. The pair of insulators 13 and 14 serve to support a rod 18 and similarly insulators 15 and 16 support a rod 19. Extending in parallel relation to rods 18 and 19, and mounted upon the side walls 11 and 12 there are positioned a pair of rods 20 and 21. Within the container there are positioned a plurality of uniformly spaced plates 23, 24, 25, 26, 27, 28, 29, 30, 31, 32, 33, 34, 35. The evenly numbered plates are mounted upon rods 20 and 21, and hence are mechanically supported by and electrically connected to container 10. The odd numbered plates extend somewhat beyond either end of the even numbered plates and are mechanically supported by and electrically connected to the rods 18 and 19, but by virtue of insulators 13—16 the odd numbered plates are electrically insulated from the container 10. The odd numbered plates are electrically charged by a conductor 36 which passes through an insulating bushing 37 in the side wall of container 10, and is electrically connected to the rod 18, and hence to the odd numbered plates. The opposite side of the electrical circuit is represented by conductor 38 which is electrically connected to the container 10, and hence to the evenly numbered plates.

The series of plates 23—35 constitute surfaces on which charged dust and other particles are precipitated in the apparatus, and hence may be designated the precipitating zone of the apparatus as indicated by the so marked bracket of Figure 1.

Beneath the precipitating plates as illustrated in Figure 1 there is an ionizing zone indicated by the bracket shown at the right in Figure 1. The ionizing zone in this instance is composed of a plurality of wires 40 which are spaced between a plurality of short plates 41, which may be solid or open construction such as a screen, or perforated material, or a grid of wires held in a

plane by an appropriate frame. The screen, or other open construction, is preferred, for ions emitted from the wires 40 may thus pass through the screen to the next zone between the next "plates" (open construction). The ions are thus not neutralized as they would be by hitting on solid plates. The wires 40 are carried by a rod or spaced rods 42, one of which is shown in the sectional view in Figure 1. The wires 40 are accordingly mechanically supported by and electrically connected to the container 10, which is preferably grounded.

The plates 41 are mounted upon rod or rods 43 which in turn support upon spaced insulators 44 attached to the container 10. The plates 41 are accordingly mechanically supported by, but are electrically insulated from the container 10 and also electrically insulated from the even numbered plates of the precipitating zone. Electrical potential is applied to the plates 41 by means of a conductor 45 which passes through an insulating bushing 46 in the side wall 11, the conductor being attached to the rod 43.

A source of alternating current having a frequency in the range from high audio frequencies to slightly lower than the low radio frequencies and having a unidirectional component is applied between conductor 38, which is attached to the container (and hence electrically connected to wires 40) and conductor 45 extending to the ionizing plates 41. The apparatus for generating and applying said potential to the common wire 38, the precipitating plate conductor 36 and the ionizing zone conductor 45 may be any one of those illustrated in Figures 3, 4 and 5, with or without variations such as illustrated in Figures 8 or 9.

Referring to Figure 2, there is illustrated one form of power pack constituting a portion of the electrostatic apparatus and system of the present invention. In Figure 2 low voltage commercial frequency alternating current is supplied to feeders L₁ and L₂, feeder L₁ being grounded as illustrated at 50. The apparatus includes a full wave rectifier generally designated 51, having cathodes 52 and 54 and anodes 53 and 55. The cathodes 52 and 54 are indirectly heated by filaments 56 and 57 which are connected in series as illustrated. Feeder L₂ is connected by conductor 58 to anode 53 and by conductor 59 to the cathode 54. Cathode 52 is connected by conductor 60 through junction 61 and line 62 to one terminal of condenser 63 and thence through the condenser, line 64, junction 65 and line 66 through condenser 67, line 68 to junction 69 and through line 70 to the anode 55. Junction 65 is connected by line 71 to junction 72 on feeder L₁. It will thus be observed that when the alternating current potential is such that L₂ is positive in respect to L₁, current will flow from L₂ through line 58, anode 53, cathode 52, line 60, junction 61, line 62, through condenser 63, line 64 to junction 65 and thence through line 71 to junction 72 on L₁. During the next half cycle when L₁ is positive with respect to L₂, current will flow from L₁ to junction 72 and thence through line 71 to junction 65, line 66, condenser 67, junction 69, line 70 through tube 51 via anode 55 and cathode 54 through line 59 to L₂. Condensers 63 and 67 are accordingly charged in the same direction by alternate half cycles of the alternating potential applied to feeders L₁ and L₂ and therefore the potential existing between junctions 61 and 69 reaches twice the crest value of the alternating poten-

tial of the supply lines, when there is no load, and is slightly less than this when loaded by the load of oscillator tube 75. The potential across junctions 61 and 69 serves as the direct current supply for the remainder of the apparatus.

An oscillator tube is illustrated at 75 and includes cathode 76, which is indirectly heated by filament 77, a control grid 78, screen grid 79, grid 80 and anode 81. Line 82 extends from junction 69 to junction 83 on the cathode connection 84 of tube 75. The cathode 76 is connected to grid 80 by an internal connection 85 of the tube, and the screen grid is connected to junction 65 by means of line 86. The screen grid is accordingly maintained at an intermediate direct current potential which is half the potential existing between junctions 61 and 69.

At 90 there is illustrated a transformer having a primary winding 91, a high voltage secondary winding 92, a low voltage oscillator feed back secondary 93 which may be air coupled, but preferably has a complete or nearly complete iron circuit 94. The core 94 is preferably composed of high grade transformer steel of .003 inch or less in thickness and may be either an open or closed iron core. One terminal of the primary winding 91 is connected by wire 96 to junction 61, the opposite end of the primary winding being connected by wire 97 to the anode 81 of the oscillator tube 75. Junction 83, which is connected to the cathode of the oscillator tube is electrically connected through line 98 and through resistance 99 and capacitance 100 (in parallel) to junction 102, which serves as one of the terminals from which direct current at high voltage is supplied by the apparatus through the common line 38 (see Figure 1). The oscillator feed back secondary 93 may be connected directly to junction 102, or, alternatively, may be connected through line 93' to line 114, in which case the connection to junction 102 is broken. The opposite terminal of the feed back winding 103 is connected through line 103 and through the grid bias resistor 104, and grid bias condenser 105 (in parallel) to the control grid 78 of the oscillator tube 75. It is sometimes desirable to connect a variable condenser 106 across the primary 91 of the transformer so as to allow tuning of the circuits for achieving the most desirable frequency of oscillation of tube 75, although in instances the inherent capacitance of the transformer 90 and related connections is sufficient to establish the necessary oscillatory relationship in the circuit, and condenser 106 may therefore be considered as optional.

The net effect of oscillator tube 75 is therefore to impress upon primary winding 91 and oscillating current of a frequency in the range from the high audio frequencies to slightly below the low radio frequencies, viz. from about 5,000 to about 30,000 cycles per second or somewhat higher, and this causes voltages to be induced in secondary windings 92 and 93.

An energizing potential of the frequency range stated has the attributes such that when the ionizing potential is applied to the ionizing zone (Figure 1) or to other appropriate precipitating apparatus, no dust particle may move through the length of the ionizing zone without having impressed thereon at least one cycle crest of ionizing potential. At the same time, the frequency is sufficiently low so as not to be in the radio frequency range so as not to cause disturbance therein. The frequency range stated also permits

the apparatus to operate successfully without added dangerous high voltage condensers, as have heretofore been used in electrostatic precipitating apparatus.

The secondary winding 92 serves as the feed back circuit for controlling the oscillation of tube 75 through the voltage applied upon control grid 78. The grid bias resistor 104 and condenser 105 operate in the usual manner to establish a grid bias upon the grid 78.

The number of turns in secondary winding 92 is large as compared to the number of turns in winding 91, and a high voltage is therefore induced between terminal 36 and the opposite end of the winding. The winding is preferably provided with an intermediate variable tap 107 which is connected by line 108 to the anode 113 of the rectifier tube generally designated 110. The rectifier tube is provided with a cathode 111 which is connected by line 114 to junction 83, and hence through line 98, and through resistor 99 and capacitor 100 (in parallel) to junction 102 and thus to the common line 38. Cathode 111 is indirectly heated by filament 112.

For convenience filaments 56 and 57 of the full wave rectifier tube 51, filament 77 of the oscillator tube 75 and filament 112 of the rectifier tube 110 are connected in series through a circuit extending from junction 115 on L_2 through line 116, resistor 117, line 118, through filaments 56 and 57 in series, thence through line 119, filament 77, line 120, filament 112 to L_1 . The resistor 117 is provided so as to limit the current through the filaments of the tubes thereby permitting the use of tubes of standard design. In the event specially designed tubes are utilized, the filaments 56, 57, 77 and 112 may be designed so as to utilize entire voltage between feeders L_1 and L_2 , and the resistance 117 may thereby be eliminated.

As a result of the voltage induced in the winding 92, between terminal 36 and tap 107, there is provided across lines 38 and 36 a unidirectional high voltage through a circuit as follows: From the common line 38, terminal 102, through resistor 99 and condenser 100 (in parallel), line 98, junction 83, line 114 to cathode 111 of the rectifier 110, thence to anode 113, through line 108 to tap 107 and through the winding 92 to terminal 36. This unidirectional high voltage is applied between the corresponding terminals 36 and 38 of a precipitating apparatus, for example that illustrated in Figure 1.

The transformer winding 92 is also provided with another variable tap 121 to which line 45 is attached. The voltage at tap 121 may be less than, equal to or greater than the voltage at tap 107, according to the mode of operation of the electrostatic precipitator, but it is preferably made greater than the voltage at tap 107 for a purpose hereinafter to be described. As a result of this mode of connection, a voltage is produced between lines 38 and 45 having a frequency in the range from high audio frequencies to slightly lower than the low radio frequencies and having a high voltage unidirectional component. The circuit producing this complex potential extends from the common line 38, tap 102, thence through resistor 99 and condenser 100 (in parallel) through line 98 to junction 83, and thence through line 114 to cathode 111 of rectifier tube 110, and to the anode 113 through line 108 to tap 107, through the portions of the winding 92 between taps 107 and 121 to line 45. The line 45 is connected to the corresponding numbered line

of the precipitating apparatus, for example as shown in Figure 1, leading to the ionizing zone of the apparatus.

Referring to Figure 6, there is shown a graph illustrating the voltage on the precipitating plates of the electrostatic precipitator and the voltage existing between the ionizing wires 40 and the plates 41 of the ionizing zone. In Figure 6 the line 123—124 represents the unidirectional voltage applied between the precipitating plates 23—35 of the apparatus shown in Figure 1, the voltage E being preferably in the range of 3,000 to 50,000 volts, depending upon the spacing of the plates and other factors. The voltage existing between the ionizing wires 40 and the plates 41 includes the unidirectional component E and upon this there is superimposed an alternating current voltage having a crest value of E' , which is preferably greater than the voltage E with the result that as the voltage E' becomes negative, a negative voltage $E' - E$ occurs at each half cycle between the wires 40 and plates 41. If the voltages E and E' are adjusted to appropriate values, in relation to the size of wire used for the wires 40, ionization will not occur until the total voltage between the wires 40 and plates 41 reaches another value E_c (voltage at which ionization occurs). Where the precipitating apparatus is utilized for the purification of air used for respiratory purposes, it is undesirable that any extensive ionization should occur in the apparatus, in as much as ionization causes the formation of ozone and oxides of nitrogen.

In order that the ionization phenomena may be limited despite the variations in line voltage occurring between lines L_1 and L_2 , the power pack includes a regulator apparatus which, in the illustrated embodiment, consists of resistance 99 and condenser 100 (in parallel) in cooperation with the remaining portions of the apparatus. The operation of the apparatus is such that when ionization begins to occur, the increased current, due to the corona formation, causes the amplitude of the oscillating currents through tube 75 to be decreased thereby decreasing the voltage to a point sufficient that the ionization is held at a pre-adjusted small but sufficient value.

Figure 7 is a graph illustrating the corona current for a wire of given size plotted against the potential applied to the wire. In Figure 7 the curve 125—128 illustrates the corona loss for ionizing wires 40 which are of given size, for example, as in Patent 1,343,285. When the voltage applied to wires 40 is below the amount E_1 , no corona occurs and the current I is accordingly zero. As the voltage reaches the amount E_1 , corona begins. As the rate of increase of corona current increases for each added increment of voltage, curve 125, 126, 127, 128 has an increasingly rising slope. By suitable adjustment (or selection of the circuit constants) of the apparatus illustrated in Figure 3, the magnitude of the voltage supplied between lines 38 and 45 can be caused to be at or slightly above the voltage E_1 on the curve shown in Figure 7 or at any selected point on the curve. If, due to an increase in line voltage applied between lines L_1 and L_2 , there is a reflected increase in the voltage between the ionizing wires 40 and plates 41, the current drawn through resistor 99 and the condenser 100 (in parallel) increases as shown by the curve 125—128, and this produces an increased potential drop across resistor 99 and the condenser 100. As a result the tube 75 oscillates

at nearly the same or at only a negligibly increased value, and consequently the voltage across the ionizing wires 40 and plates 41 (and also across the precipitating plates) is held at a value closely approximating the values existing before an increase occurred in the voltage across lines L₁ and L₂. In this manner the ionization on the wires 40 may be closely controlled to a regulated amount such that deleterious formation of ozone and nitrogen oxides does not occur in the air or other gas circulated through the purification apparatus.

It will readily be observed that the oscillator tube 75 may be adjusted so as to permit an operation at any point along the curve 125-128, and thus any degree of corona current, consistent with acceptable operation of the precipitator, may be permitted.

The secondary 93 may optionally be connected directly to line 114, as shown by line 93', rather than to junction 102 (which is in such case disconnected), and grid 79 is then connected through line 86' to junction 102 rather than to junction 65. These variations in the connections are illustrated in lines at 93' and 86' in Figure 3. If connections 86' and 93' are not used, winding 93 is simply connected directly to junction 102, with favorable results as aforesaid. Or, a tube having four grids may be used and the fourth grid connected to junction 102, the remaining grids being as illustrated. A four-grid tube is illustrated in Figure 3, hereinafter discussed. By this manner of connecting secondary 93 directly to line 114 (rather than through the resistor 99 and condenser 100), the feed back voltages controlling oscillation of the tube are isolated from the control voltage bias across resistor 99-condenser 100, which serve to maintain the output voltage at a closely regulated value.

In the apparatus of Figure 2, the full wave rectifier tube 51, together with the condensers 63 and 67 serves as a voltage doubler circuit so that the apparatus may conveniently be powered from low voltage alternating current circuits such as 110-volt circuits. Ordinary oscillator tubes, such as the tube 75, have a working internal voltage drop such that the input voltage of the tube, for most efficient operation, must be in excess of ordinary 110-volt supply line voltages. By utilizing the rectifier tube 51 and condensers 63 and 67, there is provided an exceptionally low weight apparatus for supplying the relatively high voltage between lines 82 and 96, which constitute the input of the oscillator tube.

The apparatus in Figure 2 is illustrated as utilizing an oscillator tube 75 of the pentode type, but there may likewise be utilized an ordinary triode by dispensing with grids 79 and 80 and connections 85 and 86.

Referring to Figure 3, there is illustrated a somewhat modified form of power pack in which the oscillator and rectifier portions of the apparatus illustrated under the bracket 130 are the same as the corresponding portion of the apparatus illustrated in Figure 2. However, in the apparatus of Figure 3 two full wave rectifiers generally designated 131 and 132 are illustrated, and these cooperate with a series of four condensers 133, 134, 135 and 136 to produce across lines 82 and 96 a voltage equal to four times the crest value of the alternating voltage on feeders L₁ and L₂, when the oscillator tube 75 is disconnected.

The full wave rectifier 131 includes a cathode 133 which is indirectly heated by filament 134 and

a second cathode 135 indirectly heated by filament 136. Cathode 133 cooperates with anode 137, and cathode 135 cooperates with a similar anode 138. The full wave rectifier 132 is preferably identical with the rectifier 131 and includes a cathode 140 which is indirectly heated by filament 141, and a cathode 142 indirectly heated by filament 143. Cathode 140 cooperates with an anode 144, and cathode 142 cooperates with an anode 145. The rectifiers 131 and 132 and the condensers 129, 134, 135 and 136 are connected as follows: Feeder L₁ is connected directly to one terminal of condenser 129, the other terminal of the condenser being connected through line 147 to one terminal of condenser 135. The opposite terminal of condenser 135 is connected through line 148 to anode 145 of rectifier tube 132. From junction 149 on line 147 there extends a line 150 leading to anode 138, cathode 133 being connected to junction 151 on line 150. Cathode 140 is similarly connected to junction 153 on line 148. Feeder L₂ is connected directly to anode 137 of tube 131 and to one terminal of condenser 133, the opposite terminal of condenser 25 133 being connected by line 155 to one terminal of condenser 134, the opposite terminal of which is connected by line 156 to junction 157, which constitutes one of the output voltage terminals of the voltage multiplier portion of the apparatus. Junction 157 is connected directly to cathode 142 of the rectifier tube 132. Junction 157 is connected to line 96 of the oscillator in a manner analogous to the connection of line 96 to junction 61 in Figure 2. Line 82 of the oscillator 30 35 (Figure 3) is connected to junction 158 on feeder L₁, which constitutes another output terminal of the voltage multiplier. From junction 159 on line 155 a circuit 160 extends directly to cathode 135 of tube 131 and from junction 161 on line 40 45 50 55 60 65 70 75 80 85 90 95 100 105 110 115 120 125 130 135 140 145 150 bracket 129). Therefore these parts of the apparatus of Figure 3 need not be further described in detail.

In the apparatus of Figure 3, as in that of Figure 2, the feed back and voltage regulation control voltages supplied to grid 78 may be separated and each applied separately to grids of tube 75. To accomplish this end, winding 93 is disconnected from junction 102 and is connected to line 168 as illustrated by the line 93', and a fourth grid 87 which is then used in such alternative form is connected to junction 102 as shown by the line 86'. Also grid 78 may be disconnected from junction 163 and reconnected to junction 102, where it is desired to use a three-grid oscillator tube, as shown, rather than a four-grid tube. In this way the rise in output current in line 38 produces a biasing voltage which is applied to achieve regulation via grid 87 (or grid 79), whereas the feed back voltage maintaining oscillation is applied via grid 78. It will be understood that in Figure 3, when the changed connections illustrated by the lines 86' and 93' are not used, winding 93 is then connected directly to junction 102, and the feed back oscillation control voltage and also the output voltage regulation control voltages are accordingly combined and applied on the one grid, viz. grid 78.

The devices of Figures 2 and 3 are of exceptional utility wherein low weight and low cost are of importance in as much as sufficiently high voltage for efficient operation of electrostatic precipitators, viz. 3,000 to 50,000 volts, is conveniently supplied, and sufficient current is available without the use of the cumbersome apparatus customarily used. The transformer 80 is of low weight and indeed the entire apparatus of Figures 2 and 3 weighs only a few pounds and may be housed in a space from 2-3 inches wide, 4-6 inches long and 3-4 inches high. The apparatus is accordingly admirably suited for portable electrostatic precipitator installations, and where low cost is a factor.

In Figure 4 there is illustrated an apparatus suitable for use where the power source is a low voltage direct current, for example an automobile battery of 6-12 volts. In the apparatus of Figure 4 there is utilized a vibrator, generally designated 171, of conventional design customarily used in automobile radio apparatus and includes vibrator magnet 173 and contacts 174 and 175 together with the main vibrator reed 172 and its cooperating contacts 176 and 177. Contacts 176 and 177 are connected by lines 178 and 179 respectively to the opposite terminals of a primary transformer winding 180 of transformer generally designated 181. To a mid-point tap 182 on the transformer winding there is connected a condenser 183, the opposite terminal of which is connected to junction 184 and thence to the vibrator reed 172. Junction 184 is connected by line 185, namely, to the negative low voltage supply line 186 and the mid-point tap 182 of winding 180 is connected to positive line 187. The positive voltage supply line 187 is connected by line 188 to one terminal of the vibrator magnet 173 of the vibrator assembly. Contacts 174 and 175 are in engagement when the vibrator 171 is deenergized, and when energized, the magnet 173 draws the magnetic reed 172 downwardly as illustrated in Figure 4, thus breaking contacts 174-175. Reed 172 vibrates and alternately engages contacts 176 and 177 and as a result a pulsating direct current is applied alternately in opposite directions to the two halves of the primary

winding 180 of the transformer 181. As a result a much higher voltage is induced in the secondary winding 189.

Mid-point 190 of the secondary winding 189 is connected by line 198 to junction 199 on the low voltage power supply line 186, and the end terminals of winding 189 are connected by lines 191 and 192 to the anodes 193 and 194, respectively, of the full wave rectifier generally designated 195. The full wave rectifier tube 195 is provided with a cathode 196 which is indirectly heated by the filament 197, the latter being directly connected across the low voltage leads of supply lines 187 and 186. The vibrator 171, transformer 181 and rectifier tube 195, which are indicated generally under the bracket 198 serve as a high voltage direct current supply for the input of the oscillator 75, this supply being applied across conductors 86 and 96. A condenser 207 connected between junction 208 on line 96 and junction 209 on line 186 serves to smooth out ripples in the direct current supply of tube 75.

The high frequency oscillator 75, transformer 94 and rectifier 110 of the apparatus, shown generally under the bracket 200, are similar to those shown in Figures 2 and 3, suitable changes in the wiring being made to accommodate the low voltage supply source. Thus, the oscillator 75 is provided with an indirectly heated cathode 76 which is connected to one terminal of the heating filament 77, the filament being connected directly across the low voltage supply leads 186 and 187. The grid 80 is connected externally or internally of the tube by line 85' to the terminal of filament 77 which is in turn connected to line 186. One terminal of the transformer primary winding 91 is connected by line 91 directly to the anode 81 of the oscillator tube, the other terminal of the primary 91 being connected to line 96. The feed back secondary winding of the transformer is shown at 93, one terminal of such winding being connected through a grid bias resistor 104 and condenser 103 (in parallel) to the grid 78. The other terminal of the feed back winding is connected to junction 102 to which the common output line 38 is also connected. To the junction 102 there is connected (in parallel) the voltage regulator resistor 99 and condenser 100, the opposite terminals of these elements being connected by line 85' to the cathode 76 and to the low voltage power supply line 186. If desired, the winding 93 may be connected directly to line 186 and a connection run from terminal 102 to grid 79, or a fourth grid, as explained with reference to Figures 2 and 3.

The half wave rectifier tube is shown at 110, the cathode 111 being connected to one terminal of the indirect heater filament 112, the latter being in turn connected directly to the low voltage supply lines 186 and 187. The anode 113 of the half wave rectifier is connected to tap 107 on the transformer secondary winding 92. Output line 36 constitutes one of the terminals of the unidirectional high voltage supply. From variable tap 121 on the winding 92 there extends line 45 which supplies the ionizing potential, namely a high voltage alternating potential having a frequency in the range from high audio frequencies, slightly below the low radio frequencies, and a unidirectional high voltage component.

Grid 79 of the oscillator tube is connected by line 86 to junction 202 which is in turn connected through a resistor 203 to junction 201 on line 96. A condenser 204 is connected between junction

.202 on line 86 and junction 205 on low voltage supply line 186.

Assuming that low voltage direct current is supplied to lines 186 and 187, the filaments of all of the thermionic tubes 195, 75 and 110 are illuminated and the tubes are in condition for operation. At the same time, the operation of the automotive type radio vibrator 171 supplies a pulsating direct current to the winding 180 and transformer 181, and there is accordingly induced in winding 189 a relatively high voltage alternating current which is rectified by tube 195. Under such conditions of operation the oscillator tube 75 will oscillate through a circuit as follows: Beginning at low voltage supply line 186 current flows from junction 199 to mid-point 190 on transformer secondary 189 and thence alternately through the upper and lower halves of the winding 189 and alternately to the anodes 193 and 194, thence through the full wave rectifier tube 195 to cathode 196 and through line 96 to transformer primary 91, line 97, anode 81 of the oscillator tube 75, cathode 76, through the lead of filament 77 to the low voltage supply line 186 and through the latter to junction 199. The oscillator tube 75 oscillates at a frequency from 5,000 to 30,000 cycles per second or somewhat higher as determined by the inductance and inherent capacitance of transformer 94 and the circuits associated therewith (or due to optional condenser 106 when used), whereby an oscillating current flows through the primary 91. Through transformer action a high voltage range from 3,000 to 50,000 volts (according to the design of the dust precipitator apparatus) is induced in winding 92. A relatively low voltage is induced in winding 93, and controls the oscillator tube 75. The voltage induced in winding 92 is rectified by half wave rectifier 110 as described with reference to Figure 3 and as a result, a high voltage direct current is supplied across leads 36 and 38, and a high voltage direct current together with an alternating current component is supplied between leads 38 and 45. These leads are connected to correspondingly numbered leads of the precipitator apparatus illustrated in Figure 1 or a similar precipitator.

The voltage regulation of the high voltage output between lines 38 and 45 (and also between lines 38 and 36) is achieved by the action of resistor 99 and condenser 100 as described with reference to Figure 2. Therefore, a substantially constant high voltage is applied to the ionizing zone (wires 40 and plates 41) and also on the precipitating zone (plates 23-35) and is achieved regardless of voltage variations of the low voltage supply on lines 186 and 187.

In Figure 5 there is illustrated a modified form of the invention which is similar to that illustrated in Figure 4, except that the primary 181 of the transformer generally designated 181 is energized from a suitable source of alternating current illustrated by the alternating current lines L₁ and L₂, rather than being energized with pulsating direct current as illustrated in Figure 4. In Figure 5 the filament current supply is provided by transformer secondary 210, which is connected across the low voltage supply lines 186 and 187 which in this case are energized with alternating current rather than direct current. In all other respects the apparatus of Figure 5 is similar to that shown in Figure 4.

Referring again to Figure 7, the corona current curve 125-128 is determined by the physical characteristics of the surface from which

corona is emitted, in this instance the round ionization wires 40, and by the characteristics of the surrounding atmosphere, viz. atmospheric pressure, temperature, and humidity.

At this juncture it may be noted that corona varies very appreciably with respect to atmospheric pressure, a ten percent fall in the barometer reading being roughly equal in corona-producing effect to a ten percent increase in voltage on the corona-producing surface. As the corona increases roughly as the square of the applied voltage, very serious corona increase may accompany a fall in atmospheric pressure or rise in line voltage in any unregulated precipitation system. Likewise a 10% increase in voltage, which is not at all unusual in secondary distribution systems, occasions a 50% increase in corona in an unregulated system. Where the apparatus is used for the purification of air for respiratory purposes, such an increase in corona causes a disagreeable and harmful increase in ozone and nitrogen oxides.

In Figure 7 there is illustrated a second curve 213-214 displaced from curve 125-128, illustrating the corona current of corona control wire 40' which is energized from the same supply source as that corresponding to the curve 125-128. The only variation between wire 40 and wire 40' is that the latter is somewhat larger in diameter and hence corona does not begin on wire 40' until voltage E₂ is reached, and then it increases with increased voltage as shown by curve 213-214. As a result corona does not occur for the wire 40' (curve 213-214) until the voltage has risen to a value of E₂, at which time corona, in an amount corresponding to point 126, is present on wire 40 (corresponding to curve 125-128). Precise regulation of the corona discharge of the wire 40 may be achieved by utilizing an apparatus such as that illustrated in Figures 8 or 9 in which a second wire 40' is used for corona control regulation.

Referring to Figure 8, there is illustrated a portion of the wiring diagram of the apparatus shown in Figures 2, 3, 4 or 5, this portion being transformer 90 and the regulator portion of the circuits, namely resistor 99 and capacitor 100. In addition to Figure 8 there is schematically illustrated the electrostatic precipitator apparatus of Figure 1, wherein the precipitating plates 23-35 are shown in uniformly spaced relationship, alternate plates being connected respectively to the common conductor 38 and to the high voltage direct current conductor 36. The precipitating apparatus also includes the working ionizing wire 40 together with its cooperating plates 41, the wire 40 being connected to the common conductor 38, and the plates 41 to the high voltage conductor 45 which supplies high voltage direct current having a high frequency alternating component. In addition in Figure 8 there is provided a control ionizing wire 40' together with cooperating, spaced plates 41'.

In the normal dust precipitating system such as that illustrated in Patent 1,343,285, it is desired to operate the ionizing wire at a condition of slight corona formation such that the corona produces the ionization sufficient for dust precipitation, but not enough to render the dust-free air objectionable for human respiration. Accordingly, wire 40 is operated as in Patent 1,343,285 at a voltage such as will produce a slight corona, the corona current begins, for example in the region 126-127 of the curve shown in Figure 7. Wire 40' is of a size selected such that corona

will just begin to form on the wire 40' at voltage E_2 , when corona is already developed in the limited amount indicated by point 126 on the curve 125-128 of wire 40, and is located in any convenient idle space in the precipitator unit, and out of the stream of gas going therethrough. The ionizing current for the working ionizing wire 40 and plates 41 and the control ionizing wire and plates 40' and 41' are drawn in parallel through resistor 99 and capacitor 100 (Figure 8), and the electrical constants of these elements of the circuit are appropriately selected so as to permit oscillator tube 75 (Figures 2-5) to operate at a magnitude of oscillation sufficient to allow the voltage applied to wire 40 and plate 41 to rise to the value E_2 when the total corona current drawn by wires 40 and 40' corresponds to point 126 (Figure 7). However, any increase in voltage occasioned by an increase in voltage across lines L_1 and L_2 will cause wire 40' to begin to manifest corona at the zero point 213 on the curve 213-214. Accordingly, any rise in voltage beyond E_2 (Figure 7) will effect the regulating resistor 99 and capacitor 100, and will suppress any corresponding increase in value of the oscillating current flowing through oscillator tube 75. Thus, by utilizing the control ionizing wire 40' and its associated plates 41' in parallel with working wire it is possible very sharply to control the ionizing voltage applied to the working ionizing wire 40, and by appropriate choice of size of the wire 40', it is thus possible to work at any established voltage E_2 on both wires. In this way it is possible to allow a controlled degree of ionization on wire 40 without the hazard of undue ionization which would otherwise be occasioned by a rise in voltage on the supply lines L_1 and L_2 .

Atmospheric changes such as variations in barometer, humidity and temperature, or variations in latent ionization such as cause an increase in ionization, serve automatically to achieve self-regulation. Any corona-increasing atmospheric disturbance in effect shifts both of the curves 125-128 and 213-214 to the left, parallel to their illustrated positions. Assuming the power supply voltage conditions to be constant, such a leftward shift has the effect of an increase in the applied voltage, and causes corona current to increase on wire 40 and to start on wire 40', the voltage regulation bias voltage across resistor 99 and condenser 100 immediately effects tube 75, and reduces the magnitude of the oscillations until the corona is again decreased. This functioning is characteristic not only of the apparatus of Figures 8 and 9, but also is characteristic, to a lesser degree, of the systems of Figures 2-5.

It will thus be observed that one may utilize the manifested function (corona current) as the direct agent for controlling the voltage of the power supply feeding the corona producing system. This is one of several very useful features of the invention.

In Figure 9 there is illustrated a modified form of regulating apparatus utilizing a working ionizing wire 40 and a control ionizing wire 40' of the type illustrated in Figure 8, except that the control ionizing wire is connected to a tap on resistor 99 so that the current drawn by the control ionizing wire 40' traverses the entire resistor 99 whereas the current drawn by the working ionizing wire traverses only portion 99a. By suitable choice of circuit constants of resistor 99 and condenser 100 and wire diameter of the control ionizing wire 40' and working ionizing wire 40, the system may be caused to operate in the voltage

126 (curve, Figure 7) due to the regulating action of the control ionizing wire. The portion 99a of resistor 99 may be very small, as compared with the whole of resistor 99, since the regulating effect is achieved by the ionizing current of wire 40' which is drawn through the entire resistor 99 (and condenser 100). However, should a flash-over occur between the working ionizing wire 40 and its associated plates 41 or between the alternately charged precipitating plates 23-35, the flash-over current is sufficient, when drawn through the relatively low value of resistor 99a to cause the oscillator tube to be biased to cutoff, thereby extinguishing the flash-over arc. In this manner the large increase in current due to flash-over is utilized, through the relatively small portion 99a of the regulator resistor, to achieve an equal or greater regulatory effect than ordinarily occurs during working due to small increases of ionizing current for control wire 40', drawn through the whole of resistor 99 and condenser 100. Thus resistor 99a may be chosen of a size such that a current of flash-over proportions flowing therethrough is sufficient completely to block oscillation of tube 75, and thus simply interrupt the high voltage supply.

In the apparatus of Figures 8 and 9, the winding 93 may be alternatively, the connections to 102 may be broken and winding 93 connected to junction 102, or connected by the circuit 93' to the lead corresponding to line 114 of Figure 2, 168 of Figure 3 or 85' of Figures 4 or 5. When so connected junction 102 is connected as by line 86' (Figure 3) to a fourth grid of the oscillator tube 75, or grid 79 may be utilized as the voltage regulation grid, rather than being connected to a constant voltage point of the power supply.

In any of the circuits heretofore described, the type of oscillator tube 75 should be chosen so as 40 to be capable of regulation by the ionizing currents flowing in the apparatus. Alternatively, the voltage regulating potential which is available at junction 102 may be amplified through 45 a simple single or multiple stage amplifier before being applied to the voltage regulating grid of the oscillator tube. Thus, using the potential at junction 102 as the input to an amplifier, the output thereof may be applied conveniently to line 86'. Also an adequately controlled small 50 power unit, as described above, may be used to drive a large power oscillator where large output is desired.

The control ionizing wire 40' may conveniently be housed in an air-filled tube 265, such as that 55 shown in Figure 10, which is open to the atmosphere or separated therefrom by a screen, porous plate etc., as illustrated by the dotted line 266, for allowing ready change of pressure within the tube when the atmospheric pressure changes. Or 60 the tube 265 may be sealed and provided with a sylphon bellows diaphragm 267 at an end or side wall so as to allow the pressure of the air within the tube to equalize to atmospheric pressure by flexure of said bellows. For convenience, the tube 65 is provided with a socket 268 which serves to carry the plate 41' and wire 40' by means of a squash 269. Wire 40' and plate 41' are thus protected and are removed from the flow of gases undergoing precipitation and yet are subjected 70 to the same atmospheric conditions as the air being precipitated.

Other and further modifications will be apparent to those skilled in the art without departing from the spirit of the invention illustrated, described and claimed.

What I claim is:

1. An electrostatic precipitator system comprising spaced precipitating plates, spaced ionizing electrodes adjacent the precipitating plates, and electrical means, adapted to be energized from a low voltage source for supplying a unidirectional high voltage to said precipitating plates and ionizing electrodes, and means responsive to variations in the flow of ionizing current to said ionizing electrodes occurring at voltages below those at which momentary or transient flash-over occurs for maintaining the ionizing current substantially constant.

2. An electrostatic precipitator system comprising spaced precipitating plates, an ionizing electrode adjacent the precipitating plates, and electrical means, including a low voltage oscillator, a step-up transformer and a rectifier for supplying a unidirectional high voltage to said precipitating plates and ionizing electrode, and means responsive to an increase in ionizing current output of said electrical means occurring at voltages below those at which momentary or transient flash-over occurs for biasing the oscillator to decrease the current output thereof.

3. An electrostatic precipitator system comprising spaced precipitating plates, an ionizing electrode adjacent the precipitating plates, and electrical means including a low voltage grid controlled oscillator tube, a step-up transformer and a rectifier for supplying a high voltage having a unidirectional component to said precipitating plates and ionizing electrode, and means, including a resistor connected in series with the circuit to said ionizing electrode and connected to said oscillator tube for decreasing the voltage of oscillator tube output when the current flowing to said ionizing electrode increases beyond a predetermined value.

4. The apparatus of claim 3 further characterized in that an amplifier is interposed between said resistor and the control grid of said oscillator tube for amplifying the potential of said resistor for application in controlling relation to said control grid.

5. An electrostatic precipitator system comprising spaced precipitating plates, an ionizing electrode adjacent the precipitating plates and electrical means adapted to be energized from a low voltage source for supplying a high voltage having a unidirectional component to said precipitating plates and ionizing electrode, said electrical means including a low voltage oscillator tube energized from the low voltage source and capable of oscillating at a frequency of 5,000 to 30,000 cycles per second, an iron core transformer having a low voltage primary winding connected to the oscillator tube and a high voltage secondary winding, a rectifier tube, said rectifier tube being connected in series with said secondary winding and to the precipitating plates and ionizing electrode, and a resistor also connected in series with the circuit to said ionizing electrode and to the oscillator tube for maintaining the voltage output of said oscillator tube at a level capable of supplying a substantially constant value of ionizing current to said ionizing.

6. An electrostatic precipitator system comprising spaced precipitating plates, a working ionizing electrode adjacent the precipitating plates and a control ionizing electrode, means for supplying a high voltage to said plates and electrode and means responsive to an increase of current flowing to the control ionizing electrode

for limiting the voltage applied to the precipitating plates and working ionizing electrode.

7. The apparatus of claim 6 further characterized in that the control ionizing electrode is housed in a separate chamber maintained under atmospheric pressure.

8. An electrostatic precipitator system comprising spaced precipitating plates, a working ionizing electrode capable of emitting a corona discharge at a predetermined desired voltage, a control ionizing electrode incapable of emitting a corona discharge at said predetermined voltage but capable of emitting such discharge at an increased voltage, means for supplying the same high voltage to said plates and ionizing electrodes, and means responsive to a flow of corona discharge current to the control ionizing surface for regulating the value of said high voltage.

9. An electrostatic precipitator system comprising spaced precipitating plates, a working ionizing wire and associated conductive surfaces constituting a working ionizing zone adjacent the precipitating plates, a control ionizing wire of slightly larger guage than the working ionizing wire and associated conductive surfaces adjacent thereto, means for supplying a high voltage to the spaced precipitating plates and ionizing wires, and means responsive to the flow of corona current to said control ionizing wire for regulating the voltage applied to both ionizing wires and the precipitating plates.

10. An electrostatic precipitator system comprising spaced precipitating plates, a working ionizing wire and associated conductive surfaces constituting a working ionizing zone adjacent the precipitating plates, a control ionizing wire of slightly larger guage than the working ionizing wire and associated conductive surfaces adjacent thereto, means for supplying a high voltage to the spaced precipitating plates and ionizing wires, and means responsive to the flow of corona current to said control ionizing wire for regulating the voltage applied to both ionizing wires, and responsive to the flow of arc-over current between said precipitating plates or between said working ionizing wire and its associated conductive surface for substantially reducing said voltage.

11. An electrostatic precipitator system comprising spaced precipitating plates, a working ionizing surface capable of emitting a corona discharge at a predetermined desired voltage, a control ionizing surface incapable of emitting a corona discharge at said predetermined voltage but capable of emitting such discharge at an increased voltage, means for supplying a high voltage to said plates and ionizing surfaces and resistor means in series with a conductor supplying current to said control ionizing surface and connected to said means for supplying high voltage for regulating the high voltage supplied to said plates and surfaces, for maintaining substantially constant said corona discharge from the working ionizing surface.

12. An electrostatic precipitator system comprising spaced precipitating plates, a working ionizing wire and associated conductive surfaces constituting a working ionizing zone adjacent the precipitating plates, a control ionizing wire of slightly larger guage than the working ionizing wire and associated conductive surfaces adjacent thereto, means for supplying a high voltage to the spaced precipitating plates and ionizing wires, resistor means connected in series relation with said control ionizing wire and connected to said

means for supplying high voltage for regulating the high voltage.

13. An electrostatic precipitator system comprising spaced precipitating plates, a working ionizing wire and associated conductive surfaces constituting a working ionizing zone adjacent the precipitating plates, a control ionizing wire of slightly larger guage than the working ionizing wire and associated conductive surfaces adjacent thereto, means for supplying high voltage to the spaced precipitating plates and ionizing wires comprising a relatively low voltage oscillator tube, a transformer having a low voltage primary and a high voltage secondary, a rectifier tube, the output of said oscillator tube being connected to said primary and the secondary being connected through said rectifier to the spaced precipitating plates and ionizing wires, and resistor means in series connection with said control ionizing wire and connected to said oscillating tube for regulating the voltage applied to the plates and ionizing wires.

14. An electrostatic precipitator system comprising spaced precipitating plates, a working ionizing wire and associated conductive surfaces constituting a working ionizing zone adjacent the precipitating plates, a control ionizing wire of slightly larger guage than the working ionizing wire and associated conductive surfaces adjacent thereto, means for supplying high voltage to the spaced precipitating plates and ionizing wires comprising a relatively low voltage oscillator tube, a transformer having a low voltage primary and a high voltage secondary, a rectifier tube, the output of said oscillator tube being connected to said primary and the secondary being connected through said rectifier to the spaced precipitating plates and ionizing wires, and resistor means in series connection with said control ionizing wire and connected to said oscillating tube for regulating the voltage output applied to the plates and

ionizing wires, a portion of said resistor means being connected in series relation to said working ionizing wire and precipitating plates for reducing the voltage output during flashover.

MORRIS NEWMAN

It is hereby certified that errors appear in the printed specification of the above numbered patent requiring correction as follows:

Column 14, line 29, after the numeral "93" strike out "connected to junction 102, or" and insert the same before "alternatively" in line 28, same column; and that the said Letters Patent should be read with these corrections therein that the same may conform to the record of the case in the Patent Office.

Signed and sealed this 6th day of December, A. D. 1949.

[SEAL]

THOMAS F. MURPHY,
Assistant Commissioner of Patents.
